UNITED STATES PATENT OFFICE

149,050

DESIGN FOR A CHRISTMAS STOCKING

Kathryn P. Donohue, Brentwood, Pa.

Application June 14, 1946, Serial No. 130,697

Term of patent 3½ years

(Cl. D47—7)

To all whom it may concern:

Be it known that I, Kathryn P. Donohue, a citizen of the United States, residing at 3847 Lawnview Avenue, Brentwood, Pittsburgh 27, in the county of Allegheny and State of Pennsylvania, have invented a new, original, and ornamental Design for Christmas Stocking, of which the following is a specification, reference being had to the accompanying drawing, forming part thereof.

In the accompanying drawing Fig. 1 is a front view and Fig. 2 is a side view of a Christmas stocking, showing my new design.

I claim:

The ornamental design for a Christmas stocking, as shown.

KATHRYN P. DONOHUE.
